FIG-7

UNITED STATES PATENT OFFICE

2,672,904

FOLDABLE LIQUID CONTAINER

Victor H. Hasselquist, Akron, Ohio, assignor to
The B. F. Goodrich Company, New York, N. Y.,
a corporation of New York

Application April 1, 1950; Serial No. 153,416

2 Claims. (Cl. 150—48)

1

This invention relates to a foldable liquid container which is portable in nature.

It is an object of this invention to provide a foldable container having partially self-supporting sidewalls.

It is also an object to provide such a container having a sidewall which is partially liquid supported.

It is an object to provide a container which may be folded when empty and may be carried by means of handles when filled.

Other objects will be apparent from the description and drawing which follow.

These objects are attained by making a liquid container by a dipping process wherein a form of the desired shape is dipped in a rubber latex or other similar material to deposit thereon a layer of coagulum. In general, the container comprises a base of the desired shape preferably circular in form and a sidewall having a configuration which results in a partially self-supporting wall.

To illustrate the invention more clearly a description of one embodiment will be given with reference to the accompanying drawing in which:

Fig. 1 is a perspective view showing a liquid container constructed in accordance with the invention;

Fig. 2 is a side elevation of a liquid-filled container partially broken away and in section;

Fig. 3 is a side elevation partly broken away and in section showing the form immersed in latex during the deposition step;

Fig. 4 is a sectional view of part of the form showing in detail the pins which hold the handle reinforcements in place on the form;

Fig. 5 is a cross-section on line 5—5 of Fig. 4;

Fig. 6 is a view in elevation taken on line 6—6 of Fig. 4; and

Fig. 7 is a cross-section on line 7—7 of Fig. 1.

In the drawings, numeral 11 designates the bottom of the container, and numeral 12 designates the lower portion of the sidewall 13 adjacent the bottom of the container. The lower portion 12 of the sidewall 13 normally lies flat over the margin of bottom 11 of container 14 when the container is empty as shown in Fig. 1.

When the container is filled with liquid as in Fig. 2 the angle between the bottom 11 and the lower sidewall portion 12 is increased to from 20° to 60°. The lower sidewall 12 angles inwardly so that it extends over the bottom member 11. The upper portion 15 of the sidewall 13 then angles outwardly so that it lies over the lower portion 12 of sidewall 13. The angle between

2

the lower sidewall 12 and upper sidewall 15 ranges from about 40° to about 130° depending upon the amount of liquid in the container. Secured to the upper portion 15 of sidewall 13 are the reinforced handles 16, 17.

In Fig. 3 a dipping form 18 is shown supported in the dipping position by a rod 19. The form 18 is shaped as shown with the upper surface, i. e., that part upon which is formed the bottom 11 of the container 14, being circular with a flat conical cross-section. The form 18 is preferably inverted when dipped to assure provision of a uniform deposit of coagulum on the form. The conical configuration of the form 18 facilitates removal of the form from the latex and in addition it is found to promote a uniform deposit which is free of any globules or runs of latex.

The sidewalls of the form 18 have flutes 21, 21 which run vertically and substantially parallel one to another. On the sidewalls of the form are secured pins 22, 22 which are spaced apart, two pairs being placed on each of the opposite sides of form 18, to hold the reinforcements 23, 24 for the handles 16, 17 in place while the container 14 is being formed. A small pin 25 is secured to the form 18 and positioned between each of the pairs of pins 22, 22 as shown in Figs. 5 and 6. Pins 25, 25 are designed to space the handle reinforcement 23 from the sidewall of the form 18. Since the handle reinforcements 23, 24 are spaced from the container form 18, the dipping solution surrounds the handle reinforcements 23, 24 when the form 18 is immersed as shown in Fig. 3. Pins 22, 22 in conjunction with pins 25, 25 provide a means of positioning the handle forms or reinforcing members 23, 24 until the container 18 is formed conjointly with the coated handles 16, 17.

In using the apparatus shown, each end of a handle reinforcement 23 is forced between a pair of pins 22, 22 until seated against pin 25. In like manner another handle reinforcement 24 is placed at the opposite side of the form 18. Handle reinforcements 23, 24 act as reinforcing cores as well as forms for the rubber latex to be deposited. Form 18 together with the handle reinforcements is dipped in a coagulant bath, as for example a solution of a water-soluble polyvalent metal salt such as a solution of calcium nitrate in acetone, and the coagulant allowed to dry; then the form 18 mounted on the rod 19 is immersed in the rubber latex 26 in tank 27 as shown in Fig. 3. Those portions of the form 18 which have been treated with the coagulant and

the handle forms 23, 24 are coated with a deposit of rubber latex which coagulates thereon. The handles are surrounded with deposited rubber from the latex and the deposit builds up between the handles and sidewall of the container until the handle and sidewall are joined by a continuous layer of coagulated rubber.

The form 18 is removed from the rubber latex 26 and after the handles 16, 17 are pried from between pins 22, 22 the coagulated rubber container is stripped from the form 18. The only place where trimming is necessary is around the lip of the upper wall 15. The handles 16, 17 are integrally joined with the body of the container by the deposited rubber.

The properties of the finished container are unique. When the finished container is placed upon a flat surface, the upper portion of the sidewall stands up as shown in Fig. 1. When the container is filled with water or another liquid the outward pressure of the liquid against the lower sidewall forces the lower sidewall upwardly and outwardly as shown in Fig. 2, and as a result of the lower sidewall taking such a position the upper sidewall becomes more nearly vertical as shown. Thus, the lower portion of the sidewall of the filled container arches upwardly and inwardly. The fluted reinforcements 28, 28 on the sidewall of the container 14 which are formed in flutes 21 of the form 18 lend vertical support to the sidewall when the empty container is placed on a flat surface. Of course, the upper portion 15 of the sidewall is also held in an upstanding position by the differences in diameters of the various zones of the upper and lower portions of the sidewall 13. When the container is filled with liquid and the lower sidewall is forced outwardly and upwardly as in Fig. 2, the upper portion of the sidewall remains upstanding because the reinforcements 28 tend to prevent the wall from collapsing either inwardly or outwardly. The configuration of the sidewall provides the self-supporting properties inherent therein, but the particular angles between upper and lower portions of the sidewall are not critical but may be varied considerably as long as the general configuration is retained as shown.

As is shown, the lower portion 12 of the sidewall extends inwardly from the periphery of the bottom member 11 both when the container is empty and when filled with liquid. Tension of the walls brought about by the pressure of the liquid in the container supports the lower portion 12 of the wall. The upper portion 15 of the sidewall extends outwardly from the lower portion 12 of the sidewall at all times.

The fluted reinforcements 28 also act as pleats when the container 14 is filled with liquid. The reinforcements extend from below a marginal zone 29 of the upper portion 15 of the sidewall 13 to above a marginal zone 31 of the lower portion 12 of the sidewall 13. The fluted reinforcements 28 open as would a pleat when the container is filled with liquid; thus, the diameter of the sidewall 13, within which the reinforcements are located, increases while the diameters of the marginal zones 29, 31 tend to remain constant. As a result, the sidewall tends to straighten vertically because of the forces applied by the liquid held in the container. Now it is seen the fluted reinforcements 28, 28 have a dual purpose. First, they give vertical support to the sidewall both when the container is filled and when unfilled. Also, they allow an increase in diameter of the midsection of the sidewall as a result of their

opening as a pleat opens when the container is filled with liquid. Further advantage lies in the improvement in appearance of the article.

The bottom of the container 14 is a conical shaped portion; thus, when the container 14 is placed on a flat surface, there is an excess of material at the bottom. This excess of material, although not sufficient to cause wrinkling when the container is on a flat supporting surface, is 10 of great advantage when the filled container is picked up by the carrying handles. The bottom of the container then stretches out because of the weight of the liquid. The excess material in the bottom of the container allows considerable 15 distortion of the configuration of the container with little likelihood or rupture of the bottom member or the sidewall. Since the bottom stretches rather easily because of the excess material, the liquid level in the container tends to 20 drop a little when the container is picked up. As a result of the lower liquid level, the possibility of liquid splashing over the upper edge of the container is reduced. Although when the filled container is carried by grasping the handles, the 25 configuration of the container is distorted by the weight of the material with which the container is filled, the container again assumes the shape shown in Fig. 2 when the filled container is placed upon a flat surface.

The wall thickness of the container should not be so thick that the container retains its molded shape permanently. Rather, it is best that the container may be distorted and even folded or rolled when empty. The greatest advantage of 30 such a container is that it can be folded into a very small packet which may be placed in the pocket of an article of apparel or in a lady's pocketbook, or stored in the glove compartment of an automobile.

Water can be scooped up with such a container and carried for any distance. Both handles can be grasped in one hand for easy carrying. The container is well adapted for pouring since the handles may be moved toward each 45 other to control the width of the pouring mouth of the container. By dip forming the article as an integral unit, there are no seams to tear apart or become filled with accumulations of dirt. Since the container is flexible, it may be used 50 to catch a liquid in relatively inaccessible places where metal containers cannot be inserted.

The material from which the sidewalls and bottom of the flexible container of this invention are formed may be any flexible, resilient, 55 rubber-like material, whether natural or synthetic, and the container may be fabricated by any desired method, for example by cementing together sheets of rubber having the desired shape, although it is preferred to form the article by direct deposition of the rubber-like material from an aqueous dispersion such as latex upon the surface of a form of the desired shape, as for example by dipping the form in latex. The dipping bath may be any suitable latex or a solution or dispersion of rubber or rubber-like material. The handle reinforcements or forms may be metal, fiber, paper, rubber, fabric, a thermoplastic or any other suitable material.

This invention is especially useful in providing 60 a foldable, portable container for water and other liquids or a container to be used as a carrying bag for any article which will fit therein. A container made as herein described may be used by campers, bathers, tourists, gardeners, and others. The container can be used as a wash basin,

foot basin, washtub for clothes, drinking dish for small animals, pail or as a bag for carrying bathing suits and towels.

Other advantages and uses of the finished product are apparent. While the invention has been described with reference to a specific embodiment in the example, it is not my intention to be limited thereto, for variations and modifications of the invention are possible without departing from the spirit and scope of the appended claims.

I claim:

1. A readily collapsible liquid container comprising a flexible bottom portion of rubber-like material, said bottom portion being incapable of maintaining its shape without support, a flexible lower sidewall portion extending inwardly from the periphery of said bottom portion and overlying the marginal area of said bottom portion, said lower sidewall portion being formed of rubber-like material and normally lying collapsed on said marginal area of said bottom portion when the empty container is supported on a flat surface, and a flexible upper sidewall portion extending upwardly and outwardly from said lower sidewall portion, said upper sidewall portion being formed of rubber-like material, said lower and upper sidewall portions being fluted across the intersection thereof in a direction generally normal to said intersection, said fluting providing support for maintaining the upper sidewall portion in its upstanding position while permitting elastic deformation thereof.

2. A readily collapsible liquid container of flexible elastic rubbery material, said container having a generally circular bottom portion normally biased to a generally flat conical shape with its

apex directed downwardly, said bottom portion being incapable of maintaining its shape without support, a generally annular lower sidewall portion extending inwardly from the periphery of said bottom portion and overlying the marginal area of said bottom portion, said lower sidewall portion normally lying collapsed on said marginal area of said bottom portion when the empty container is supported on a flat surface, an upper sidewall portion extending upwardly and outwardly from said lower sidewall portion and normally biased toward a downwardly directed conical section overlying the projected area of said lower sidewall portion, said lower and upper sidewall portions being fluted across the intersection thereof in a direction generally normal to said intersection, said fluting providing support for maintaining said upper sidewall portion in its upstanding position while permitting elastic deformation thereof, and means for carrying said container secured to diametrically opposed regions of said upper sidewall portion.

VICTOR H. HASSELQUIST.
